UNITED STATES PATENT OFFICE.

JOHN C. PARK, OF JEFFERSON, GEORGIA, ASSIGNOR OF ONE-HALF TO
ANTONY W. POTTS, OF SAME PLACE.

WAGON-BRAKE.

SPECIFICATION forming part of Letters Patent No. 288,659, dated November 20, 1883.

Application filed June 8, 1883. (No model.)

To all whom it may concern:

Be it known that I, JOHN C. PARK, a citizen of the United States, residing at Jefferson, in the county of Jackson and State of Georgia, 5 have invented a new and useful Wagon-Lock, of which the following is a specification, reference being had to the accompanying drawings.

This invention relates to automatic wagon-brakes; and it has for its object to produce an automatic brake which shall possess superior advantages in point of simplicity, durability, ease of operation, and certainty of action and general efficiency.

15 To this end it consists in the improved construction and arrangement of parts, which will be hereinafter fully described, and particularly pointed out in the claim.

In the drawings hereto annexed, Figure 1 is 20 a perspective view of the running-gear of a wagon equipped with my improved brake. Fig. 2 is a longitudinal vertical sectional view of the same, and Fig. 3 is a view illustrating a modification.

25 The same letters refer to the same parts in all the figures.

A in the drawings designates the front, and B the rear, axle of an ordinary wagon running-gear, which said axles are mounted upon the 30 wheels C.

D D designate the front hounds, E the sand-board, and F the front bolster.

G is the rear bolster, and H H the rear hounds.

35 I represents the reach or coupling-pole, which is mortised, in the usual manner, into the rear axle, and the front end of which has a slot, J, to receive the king-bolt K, by which it is connected to the front axle, and upon

40 which it will thus be seen that the said coupling-pole is capable of a longitudinally-sliding motion. Placed on top of the reach or coupling-pole is an iron plate, L, the front end of which is pivoted upon the king-bolt. The rear hounds are connected with the coupling-pole by the lynchpin M, which passes through

45 a slot, N, in the cap-plate L. It will thus be seen that the coupling-pole and the rear axle, with its attachments, are capable of sliding

longitudinally in relation to the front axle, 50 while the cap-plate L remains stationary.

O is a rod, of round iron or other suitable material, at the center of which is formed an eye, P, to receive a pin, Q, by which it is pivoted upon the cap-plate L, in front of the hind 55 wheels. The ends of the rod O are bent or curved so as to clear the rear hounds, and they carry the brake-shoes R R, which may be of any suitable construction.

One of the bolsters, preferably the front one, 60 has a shallow groove or recess, S, in which is seated a long roller, T, upon which rests the wagon-body or load supported upon the bolsters. When this roller is applied to the front bolster, as shown in the drawings, it will permit the wagon-body to move longitudinally, together with the reach and the hind running-gear. When applied to the rear bolster, it will prevent friction between the body or load and the rear running-gear, thus permitting 70 the latter to move freely longitudinally, as stated.

The operation of this invention will be readily understood from the foregoing description, taken in connection with the drawings hereto 75 annexed. On level roads, or in going uphill, the brake mechanism will be out of operation; but in going downhill the hind part of the running-gear will slide forward until the wheels engage the shoes upon the brake-bar pivoted 80 upon the stationary cap-plate L, thus retarding the progress of the vehicle.

I prefer that the body or load should have a longitudinally-sliding motion upon the front bolster, for the reason that the weight of the 85 load will tend to make the operation of the brake mechanism more certain.

In Fig. 3 of the drawings I have shown a modification of the invention, which consists in simply bending the cap-plate L up over the 90 rear hounds and pivoting the brake-bar, which in this case is made of wood, to the under side of the said cap-plate. The operation is precisely the same as before.

This invention, as will be readily seen, is 95 susceptible of various modifications without departing from the spirit and scope of the invention. In view of this I do not limit myself

to the precise construction and arrangement of parts herein shown; but,

Having thus described my invention, I claim and desire to secure by Letters Patent of the 5 United States—

The combination, with the running-gear constructed as herein described, of the longitudinally-movable rear axle, the cap-plate pivoted upon the king-bolt, and the brake-bar O, pivoted upon said cap-plate, said brake-bar consisting of an elastic metal rod formed with a

central eye, P, to receive the pivoting-pin Q, and having shoes R attached to its outer ends, which are curved, so as to clear the rear hounds, as set forth.

In testimony that I claim the foregoing as my own I have hereto affixed my signature in presence of two witnesses.

JOHN C. PARK.
